UNITED STATES PATENT OFFICE

EUGENE ORA DANIELS, OF TOLEDO, OHIO

DUPLEX BURNER

Application filed July 18, 1928. Serial No. 293,773.

The present invention relates to improvements in burners and pertains more particularly to burners used in conjunction with gas or oil which has been suitably heated to generate a gas, and has for its principal object to provide a structure of this type that is especially adapted to be used in connection with small and large hot water heaters, stoves, furnaces, kettles and the like.

One of the important objects of the present invention is to provide a burner that includes smaller and larger burner heads, for use dependent upon the object that is to be heated.

A further object of the invention is to provide a burner capable of using as a fuel, gas or oil, and wherein the burner includes a particular form of flame director unit for directing the heat produced to a surface or surfaces to be heated, and further to so superheat the fuel, whether it be oil or gas, to such an extent that a more perfect combustion is obtained.

Still a further object is to provide a burner of the above mentioned character, wherein means is provided for regulating the supply of gas and air to the burner head.

A further object resides in the provision of a burner of the above mentioned character which is simple in construction, inexpensive, strong and durable, and further well adapted to the purpose for which it is designed.

Other objects of the invention reside in the novel arrangement as will become apparent as the nature of the invention proceeds and when taken in connection with the accompanying drawings.

In the accompanying drawings, forming a part of this application and in which like numerals designate like parts throughout the several views:

Figure 1 is a vertical sectional view through the duplex burner embodying my invention.

Figure 2 is a view partly in elevation and partly in section of the burner for more clearly disclosing the relationship of the an-

nular burner head with respect to the flame deflector unit.

Figure 3 is a top plan view of the annular burner head.

Figure 4 is a top plan view of the flame deflector unit.

Figure 5 is a view partly in elevation, and partly in section of one form of the gas and air mixing device that is detachably secured to the inlet nipple associated with the hollow cross arm of the annular burner head.

Figure 6 is a sectional view taken approximately on the line 6—6 of Figure 5, looking downwardly.

Figure 7 is a similar view taken on the line 7—7 of the same figure, looking in the direction of the arrows, and

Figure 8 is a transverse section taken on the line 8—8 of Figure 5, looking downwardly, and

Figure 9 is a detail sectional view taken at right angles with respect to the mixing device illustrated in Figure 1 of the type of mixer shown in this figure.

In the drawings, wherein for the purpose of illustration is shown the preferred embodiment of my invention, the numeral 1 designates a substantially annular burner head that is elliptical in cross section as more clearly disclosed in Figures 1 and 2 of the drawings.

The hollow cross arm 2 which is also of elliptical formation in cross section extends diametrically across within the confines of the annular burner head and communicates at its respective ends with the adjacent portions of said burner head. Formed in the upper face of the annular burner head 1 is the annular flame discharge passage 3 and the same is disposed at a predetermined angle as more clearly indicated in Figures 1 and 2, whereby the circular flame will be directed inwardly and upwardly against the outer face of the saucer like flame deflector unit, the construction of which will be hereinafter more fully described.

This hollow cross arm is formed at its intermediate portion at the bottom thereof with the internally threaded circular neck 100

4 that extends around a gas and air inlet 5 formed in the bottom of this hollow arm and removably secured at its upper end within the depending neck 4 is the nipple 6.

5 The annular burner head 1 is furthermore formed at its outer peripheral side with the mixed fuel inlet nipple 7 which is located in alignment with the hollow cross arm 2, and a removable plug 8 is 10 threaded in this nipple for closing the same, when the mixed fuel is supplied to the annular burner head, through the inlet opening 5.

Obviously, when the fuel is supplied to 15 the burner head 1 through the nipple 7, a plug similar to that shown at 8 is threaded in the neck 4.

20 Forming the salient part of the present invention is the flame deflector unit, denoted generally by the reference character 9 and the same includes a hub 10 from which extend, at spaced points the radial arms 11 that have connection at their outer ends with the lower edge of the saucer-like 25 rim portion 12, as more clearly suggested in Figure 4. An upwardly directed annular flange 13 is formed on the upper edge of the rim 12 and a shoulder 14 is formed on the inner face of this flange 13 as clearly 30 shown in Figure 4 to provide a rest for the cylindrical shell 15, that fits snugly within the flange 13 as shown in Figure 1.

An annular skirt portion 16 depends 35 from the lower edge of the rim portion 12 and the outer diameter of this skirt portion 16 is less than the inner diameter of the annular burner head 1 as suggested very clearly in Figure 2 and this skirt portion 16 extends downwardly within the 40 confines of the annular burner head, said skirt portion being notched at diametrically opposite points as at 17 to engage over the elliptical shaped cross arm 2 and the hub portion 10 rests on the central portion 45 of the cross arm, so that said cross arm provides a support for the flame deflector unit 9 and by having the skirt portion 16 spaced from the inner peripheral face of the annular burner head 1, an annular air passage 18 is provided between the annular burner head 1 and the skirt portion 16. Furthermore, the radial arms 11 are so formed on 50 their bottom faces as to engage with the hollow cross arm 2 at only two points and air passages 19 are formed between these radial arms 11 as shown in Figure 4.

Cross arm 2 is formed with a mixed fuel 55 outlet nipple 20 that extends upwardly from the top of the central portion of this cross arm for disposition through the hub 10 and the upper portion of this nipple that projects beyond the top of the hub is externally threaded for receiving the cap shaped burner head 21 that is formed with 60 the radially disposed hollow arms 22 that

have communication with the interior of the burner head, and each of these arms is formed at its outer end with a flame discharge orifice 23. As clearly shown in Figure 1, the outer ends of these arms 22 70 terminate inwardly of the saucer-like rim 12 of the flame deflector unit, so that the flames will be directed against the inner face of this rim portion and thence deflected upwardly. 75

This burner head is used for quickly heating a receptacle supported above the burner head 21, in any appropriate manner, and when this burner head is not to be used, the same can be removed and a 80 threaded cap positioned on the upper end of the outlet nipple 20 to provide a closure therefor.

With reference now to Figures 1 and 9 of the drawings, wherein there is disclosed 85 one form of the mixer that also constitutes an important part of the present invention, it will be observed that the mixer comprises a cylindrical shell 24, that is open at its upper end and is of such diameter as to slidably receive the nipple 6 and for the purpose of securing the shell in any vertically adjusted position on the nipple, there is provided a set screw 25 that is threaded through an opening formed in 90 the upper portion of the shell and the inner end of this set screw engages with the nipple 6 in the manner as clearly indicated in Figure 1.

An annular shoulder 26 is formed on the 100 inner wall of the shell 24, at the intermediate portion thereof, to provide a stop that is adapted to be engaged by the lower end of the nipples 6, whereby to limit the upward sliding movement of the shell on the nipple. 105

A horizontal partition 27 is arranged in the lower portion of the shell 24, intermediate the bottom of said shell and the shoulder 26, as is shown in Figure 1, whereby to devise or form an upper mixing chamber 28, 110 and a lower gas chamber 29. This partition is formed with a central gas discharge orifice 30. One side of the mixing chamber 28 is cut-away as at 31, in Figure 9, to provide a relatively large air inlet opening. 115 The gas is supplied to the chamber 29 through the medium of the gas supply pipe 32 that extends upwardly in an opening formed in the bottom of the shell 24, as shown in Figure 1. 120

The gas and air will become admixed together in the chamber 28, and the fuel will pass upwardly through the nipple 6 into the hollow cross arm 2 and from this cross arm the fuel is admitted to the annular burner head 1 and when the fuel is ignited at the circular opening 3, the flame will project inwardly and upwardly against the outer face of the saucer like rim 12. Additional air will be directed against the outer wall 130

of the rim 12, to aid in the better combustion of the fuel with the air.

In Figures 5, 6, 7 and 8, there is shown a detailed construction of a modification of the mixer and the same will now be specifically described. A shell 33 is slidably fitted over the nipple 6 and secured thereon by means of the set screw 34. An annular shoulder 35 is formed on the inner wall of the intermediate portion of the shell with which engages the lower edge of the nipple as shown very clearly in Figure 5.

A partition 36 is arranged horizontally in the shell 33, in spaced relation with respect to the shoulder 35, whereby to provide an upper mixing chamber 37 and a lower gas chamber 38.

One side of the mixing chamber 37 is cut away as shown at 39, in Figure 7, to provide a relatively large air inlet opening. The gas chamber 38 is formed with side inlet openings shown at 40 and 41 respectively in Figure 8, to accommodate gas supply pipes, and when only one of said openings 25 is used, the other is closed by means of an appropriate plug.

The central portion of the partition 36 is enlarged and is formed with a gas discharge orifice 42, that tapers smaller toward its upper end and cooperating with this gas discharge orifice is the pointed upper end of a needle valve 43, the major portion of the stem of which is threaded and the lower end of the shell is formed 35 with a threaded opening through which this threaded stem extends. An actuating handle 44 is associated with the lower projecting end of the valve stem to facilitate rotation thereof whereby the needle valve 40 45 may be moved into engagement with the discharge orifice or away from the same to regulate the flow of the gas to the mixing chamber 37.

A knurled nut 46 is threaded on the lower 45 portion of the stem 43 for engagement with the boss 47 formed on the bottom of the shell 33 to secure the needle valve in any predetermined adjusted position.

For the purpose of regulating the supply 50 of air that is admitted to the chamber 37, I provide the split band 48 that encircles the shell 33 and is adapted for slidable movement thereon to partially or entirely cover the cut-out portion 39. The free ends of 55 this split band are disposed laterally to provide parallel spaced ears 49 that are formed with registering openings to accommodate a bolt 50 and a nut 51 is threaded on the threaded end of the bolt to clamp the ears 60 together whereby to secure the band 48 in any adjusted position on the shell, as is obvious from the construction disclosed in Figures 5 and 6.

It will thus be seen from the foregoing 65 description that I have provided a duplex

burner that includes a relatively small burner head and a relatively large burner head, and that both may be used in conjunction with one another, and that the relatively smaller burner may be quickly and 70 easily removed when it is desired to use but the large burner head, together with means for closing the opening 20 after the small burner has been removed.

The simplicity of my improved burner 75 enables the parts to be readily and easily assembled or disassembled, and furthermore, the same will at all times be positive and efficient in its operation.

While I have shown the preferred embodiment of my invention, it is to be understood that various changes in the size, shape and arrangement of parts may be resorted to, without departing from the spirit of the invention or the scope of the appended 80 claims.

I claim:

1. In a burner of the class described, an annular hollow burner head formed with a fuel outlet, a circumferentially extending 90 passage in the top thereof, a hollow cross arm extending across the annular burner head and arranged within the confines thereof, the ends of the cross arm having communication with the respective sides of the 95 burner head, a fuel inlet having communication with the hollow cross arm, a flame deflector unit including a saucer like rim adapted for disposition above the annular burner head, and against which the flames 100 are directed, and a skirt portion depending from the lower edge of the rim for disposition within the confines of the annular burner head, said skirt portion being notched to 105 rest on the cross arm.

2. In a burner of the class described, an annular hollow burner head formed with a fuel outlet, a circumferentially extending 110 passage in the top thereof, a hollow cross arm extending across the annular burner head and arranged within the confines thereof, the ends of the cross arm having communication with the respective sides of the burner head, a fuel inlet having communication 115 with the hollow cross arm, a flame deflector unit including a saucer like rim adapted for disposition above the annular burner head, and against which the flames are directed, and a skirt portion depending from the lower edge of the rim for disposition 120 with the confines of the annular burner head, said skirt portion being notched to rest on the cross arm, a fuel outlet nipple extending from the intermediate portion of the hollow cross arm, a cap-like burner head 125 removably secured on the upper end of said nipple for disposition within the central portion of said flame deflector unit, said cap-like burner head being provided with radial outlet openings for projecting the flames 130

against the inner wall of the saucer like rim.

3. In a burner of the class described, an annular hollow burner head formed with a fuel outlet, a circumferentially extending passage in the top thereof, a hollow cross arm extending across the annular burner head and arranged within the confines thereof, the ends of the cross arm having communication with the respective sides of the burner head, a fuel inlet having communication with the hollow cross arm, a flame deflector unit including a saucer like rim adapted for disposition above the annular burner head and against which the flames are directed, and a skirt portion depending from the lower edge of the rim for disposition within the confines of the annular burner head, said skirt portion being notched to rest on the cross arm, a fuel outlet nipple extending from the intermediate portion of the hollow cross arm, a cap-like burner head removably secured on the upper end of said nipple for disposition within the central portion of said flame deflector unit, said cap-like burner head being provided with radial outlet openings for projecting the flames against the inner wall of the saucer like rim, said flame deflector unit further including a hub through which the aforementioned nipple projects, and arms extending radially from the hub and connected at their outer edge to the lower edge of said rim.

4. In a burner of the class described, the combination of an annular hollow burner head formed with a fuel outlet, a circumferentially extending passage in the top thereof, a hollow cross arm extending across the annular burner head and arranged within the confines thereof, the ends of the cross arm having communication with the respective sides of the burner head, a flame deflector unit including a saucer like rim for disposition about the annular burner head and against which the flames are to be directed, and a skirt portion depending from the lower edge of the rim for disposition within the confines of the annular burner head, said skirt portion being notched to rest on the cross arm, and said cross arm having an inlet opening, a shell associated with the arm and having an open end communicating with the said inlet opening in said arm, a partition arranged within the lower portion of the shell and dividing the same into a lower gas chamber and an upper mixing chamber, one side of the mixing chamber being provided with an air inlet opening, a gas supply pipe receiving opening formed in the gas chamber, and said partition being formed with an orifice to admit the gas from the chamber to mix with the air in the shell.

In testimony whereof I affix my signature.
EUGENE ORA DANIELS.
